COMBINATION LIFE AND SWIMMING BELT

Eric Mazza, New York, N. Y.

Application October 6, 1941, Serial No. 413,851

4 Claims. (Cl. 9—17)

This invention relates to new and useful improvements in inflatable belts and relates more particularly to a novel combination belt which may be used by persons learning to swim, and may further be employed as a life-saving belt to be worn on all occasions by persons traveling by water.

One of the principal objects of the present invention is the provision of a novel inflatable belt which, when deflated, may be worn under the garments of the user without any discomfort whatsoever, and without any visible evidence of the belt being worn. When so deflated, the belt of the present invention is so shaped as to lie flat against the body just above the waist portion of the user, and may be worn without any discomfort or even any appreciable awareness of the fact that the belt is being worn.

One of the particular improvements in the belt of the present invention resides in the provision of a tubular portion extending upwardly from the front inflatable section, such tubular extension having a valve structure at its upper end to permit inflation of the belt by the user, such upper end having associated therewith an adjustable ribbon or cord which passes around the neck of the user. Thus, the inflating valve is readily and instantaneously accessible to the user, and when used by a fisherman, a boat enthusiast, a soldier in a landing party, or any other person having association with the water, the belt may be deflated under all normal conditions. In the event of any kind of accident wherein the user is suddenly immersed in the water, he may quickly place the valve to his lips and within a few seconds inflate the belt sufficiently to keep him afloat.

The belt of the present invention is also particularly useful for bathers who may be accomplished swimmers, but nevertheless desire to take that added precaution, the lack of which has been responsible for many drownings. In this instance, the strap or ribbon around the neck may be lengthened sufficiently to permit the tubular extension and the valve to be normally covered entirely by the bathing suit, and the casual observer will be entirely unaware of the belt being so worn. In case of a sudden cramp or an undertow quickly drawing the swimmer offshore, he will keep calm in the assurance that he may instantly raise the valve to inflating position by drawing the strap upwardly.

Another object of the present invention is the provision of a bathing or life-saving belt having an improved valve structure adapted for manual

inflation of the belt which is simple in construction, reliable in operation, and always ready for use.

Other objects of the invention will be herein-after specifically pointed out, or will become apparent as the specification proceeds.

In the drawing:

Fig. 1 shows a belt constituting one embodiment of the present invention in place upon the body of the wearer.

Fig. 2 is a plan view of such device spread out flat.

Fig. 3 is a rear view of the structure shown in Fig. 2.

Fig. 4 is an enlarged detail view, partly in section, of one form of improved valve structure of the present invention.

Fig. 5 is a top plan view of the valve structure shown in Fig. 4.

20 The belt shown in the drawing is illustrative of one of the many possible embodiments of the present invention, and it will be quite apparent that many changes and modifications may be made therein without departing from the spirit 25 of the invention as defined by the appended claims.

This embodiment includes a front section 10 and a rear section 11, such sections being inflatable and being interconnected by means of an 30 intermediate tubular section 12. Sections 10, 11 and 12 are desirably formed from two blanks of any suitable flat, flexible material impervious to the flow of air therethrough. These blanks may be formed from sheet rubber or any fabric suitably treated with rubber or other composition material to seal the air within the several sections. It is preferred, however, that the belt be formed from sheet material which is impervious to the passage of air therethrough at all times, 40 some materials requiring a thorough wetting before the pores are sufficiently sealed to retain the air. It is apparent, of course, that material of this latter type can be used for forming the belt of the present invention, particularly where the 45 belt is to be used for swimming purposes only.

Of the two blanks forming the sections 10, 11 and 12, the rear blank 14 is cut to the shape shown by the outer line in Fig. 3. The second blank 15 forming the front portion of the belt 50 is made slightly larger to provide overlapping marginal edges 16 which are cemented or otherwise secured around the marginal edges of blank 14, as shown in Fig. 3. It will be readily apparent that the belt of the present invention may be 55 formed from a single blank having a longitudinal

fold line and secured along its other edges by any suitable means.

In order to cause the belt to lie flat against the body of the wearer when deflated, the construction illustrated in Figs. 2 and 3 is preferable, although the invention is by no means limited thereto. A buckle 17 is carried by a short strap 18 which is adhesively or otherwise secured to one end of the belt, and a cooperating belt portion 19 is secured at the opposite end of the belt. If desired, portions 18 and 19 may be formed integrally with the belt. It is also obvious that any other fastening means may be employed, and the belt could, if desired, be made endless, although this particular type of construction is not the most effective for the present purposes.

Blanks 14 and 15 are provided with upwardly extending portions formed integrally with, or secured to, front section 10, thus forming a substantially flat tubular extension or feed tube 21, and a valve structure 22 is suitably secured at the upper end of this tubular extension. It is apparent that any suitable type of valve structure may be employed in connection with the present invention, such as a valve structure wherein the valve member is automatically seated by spring pressure or by pressure of the air within the device. The valve may also constitute a structure wherein the valve member is manually closed. It is preferred, however, to employ the valve structure illustrated in Fig. 4 which comprises a tubular portion 24 formed with an annular recess 25 at its lower end, such recess receiving the upper end 26 of tubular extension 21 which is cemented thereto.

Tubular portion 24 is preferably provided with an integrally formed upper wall 27 having one or more apertures 28 through which the air may pass from the user's mouth. A substantially centrally disposed aperture 29 receives a screw 30 provided with a lower headed portion 31, the screw further carrying above wall 27 a nut 32 which may be spherical or otherwise shaped. The valve member, in this instance, comprises a flat disc 34 of slightly less diameter than the inner diameter of the tubular portion 24, and when the nut 32 is tightly screwed, as shown at Fig. 4, the valve structure is closed.

When it is desired to inflate the valve, the nut 32 is loosened, thereby unseating the valve member 34, after which the tubular portion 24 is placed in the mouth and the belt inflated. During this operation, the head 31 of screw 30 will not permit the valve member to move far from its seat, and the pressure within the belt will be sufficient to close the valve after each application of air. After the belt has been fully inflated, the nut 32 is again manipulated to positively seal the valve within the belt.

An elongated strip 37 of rubber or other suitable material may be secured to the external periphery of the valve structure in the manner shown in Figs. 1 to 3, such strip having apertures 38 in the end portions thereof which extend laterally from the valve structure and which receive a cord or strap 39 which passes around the neck of the user, as shown in Fig. 1. This strap may constitute an ordinary fabric ribbon which is tied in a knot or a bow, or it may have a snap fastener or any other means for securing its ends. The strap is preferably of sufficient length, however, to permit the tubular extension 21 and the valve structure 22 to be entirely enclosed by the suit of the wearer indicated at 40. In Figs. 4 and 5 the elongated strip 39 is eliminated and a

short, vertically disposed strap 42 is cemented or otherwise secured to one side of the valve structure, such strap carrying a conventional buckle 43. On the other side of the valve structure a strap 44 is secured, such strap extending around the neck of the wearer, this strap having a plurality of apertures at its opposite end (not shown) for engagement by the buckle. If desired, an annular strip 45 may be secured around the lower terminals of the several straps. The valve structure may be either oval-shaped in plan, as shown in Fig. 5, or may be round, or any other shape. In the event that it is oval-shaped, as shown, the valve member is elongated, and in this case it is necessary to prevent rotation of the valve member 34 which is accomplished by forming screw 47 with opposed flat sides, and shaping the aperture in upper wall 27 similarly.

The number of blanks of the rubberized or other suitable material used in forming the inflatable section is strictly a matter of choice, and if desired each section may be separately formed and then the several sections, including the tubular extension, vulcanized, cemented, or otherwise secured together. In this way, there is little or no waste material, since the several blanks can be conveniently nested.

It will be apparent that the inflatable belt of the present invention will find many users who have not heretofore taken any precaution against drowning, since it in no way interferes with free movement of the body in any activity in which the wearer may indulge. It is quickly secured in place, even without removing one's garments, and may be worn, if desired, while only slightly inflated, as, for example, if one is taking a canoe trip and merely desires sufficient protection to stay afloat should the boat capsize. It gives the beginner in swimming greater courage to learn the art, and is sufficiently unnoticeable, even while inflated, as to remove the usual objection to devices of this character.

What I claim is:

1. An inflatable belt of the character described formed from a plurality of blanks of material substantially impervious to air and including interconnected front and rear sections formed so as to lie flat against the waist portion of the wearer when deflated, means detachably connecting the free ends of the front and rear sections, and a flat tubular portion extending upwardly from the front section of sufficient length to permit inflation of the belt while in secured position on the body of the wearer, a valve structure associated with the upper terminal of said tubular portion, and a flexible member extending around the neck of the wearer for normally supporting said upper terminal in an elevated position accessible to the mouth of the wearer.

2. A combination swimming and life-saving belt of the class described comprising a front section, a rear section, a tubular section of reduced width connecting said sections, means for securing the free ends of the front and rear sections around the body of the wearer, and means for permitting the wearer to inflate the several sections while in such position, such means comprising flat tubular portion extending upwardly from the front section of sufficient length to reach the wearer's mouth, a valve structure associated with the upper terminal of said extension, and means also associated with said terminal to position the valve adjacent to the neck of the wearer.

3. A combination swimming and life-saving

belt of the class described comprising an inflatable member formed so as to lie flat against the body of the wearer when deflated, including a front section, a rear section, a tubular section of reduced width connecting said sections, means for detachably securing the free ends of the front and rear sections around the body of the wearer, and means for permitting the wearer to inflate the several interconnected sections while in such position, such means comprising a flat tubular portion extending upwardly from the front section of sufficient length to reach the wearer's mouth, a valve structure associated with the upper terminal of said tubular portion, and including an apertured casing, a valve member provided with a stem passing through said aperture, the valve member being retained in closed position by the air pressure within the inflatable member, and means for positively securing the valve member in closed position, and means also associated with said terminal to position the valve adjacent to the neck of the wearer.

4. An inflatable belt of the character described formed from a plurality of blanks of material substantially impervious to air and including interconnected front and rear inflatable sections formed so as to lie flat against the waist portion of the wearer when deflated, means for detachably connecting the free ends of the front and rear sections, a flat tubular portion extending upwardly from the front section of sufficient length to permit inflation of the belt while in secured position on the body of the wearer, and a valve structure associated with the upper terminal of said tubular portion, means for supporting the upper terminal adjacent to the head of the wearer comprising a strap secured on one side thereof, extending around the neck of the wearer, and a cooperating fastening member secured on the other side thereof.
